UNITED STATES PATENT OFFICE.

JULIUS HELLER, OF VIENNA, AUSTRIA-HUNGARY, ASSIGNOR TO THE FIRM OF SCHRAUBEN-UND SCHMIEDEWARENFABRIKS AKTIENGESELLSCHAFT BREVILLIER & CO. UND A. URBAN & SÖHNE, OF VIENNA, AUSTRIA-HUNGARY.

PROCESS OF ROLLING IN RECESSES IN BLANKS.

967,768.

Specification of Letters Patent. Patented Aug. 16, 1910.

Application filed March 6, 1909. Serial No. 481,586.

To all whom it may concern:

Be it known that I, JULIUS HELLER, a subject of the Emperor of Austria-Hungary, residing at Vienna, Empire of Austria-Hungary, have invented certain new and useful Improvements in the Process of Rolling in Recesses in Blanks; and I do hereby declare the following to be a full, clear, and exact description of the invention, such as will enable others skilled in the art to which it appertains to make and use the same.

This invention relates to rolling processes and machines in which the treatment of the work is effected by means of tools which have the shape of a groove at the working surface. In this treatment however the material is forced or displaced from the points of the work treated and forms a kind of bur and the said displacement mostly alters in an undesirable manner the shape and the dimensions of the work treated, the material forced out by the tool indentations pressing against the other layers of material and forcing or displacing them beyond the original surface of the work.

According to this invention, the material constantly pressed out or displaced during the rolling beyond the desired limiting surface is cut away by means of one or more suitable cutting tools, so that no preliminary or subsequent treatment of the work is required, and in spite of that, the movement of material produced by the displacement does not result in any change of the shape or dimensions of the work.

In the accompanying drawings—Figure 1 shows the end of a bolt blank. Fig. 2 shows the same bolt, partly in section, with the threads cut thereon and projecting outwardly beyond the surface of the bolt. Fig. 3 shows the end of another form of a bolt blank with the end turned down when it is desired to cut a thread thereon of the same diameter as the main part of the bolt. Fig. 4 is a similar view, partly in section, showing the bolt blank with the thread cut thereon. Fig. 5 is an end view, partly in section, showing a bolt blank and the jaws of the rolling mechanism in section, the bolt itself being also shown partially in section. Fig. 6 is a similar sectional view taken at right angles to the section plane of Fig. 5. Fig.

7 is a top view in section, showing the action of the parts illustrated in Fig. 5, and also showing the means for cutting off the edges of the thread. Fig. 8 is a similar cross-sectional view of the parts shown in Fig. 6. Fig. 9 is a diagrammatic view showing the various stages of the rolling process. Fig. 10 shows, in side elevation, a part of the end of a bolt blank with one of the dies and the knife not yet engaged therewith. Fig. 11 is an end view of the same. Fig. 12 shows the blank as yet untouched. Fig. 13 is a view similar to Fig. 10, showing one of the dies as it begins to cut the blank. Fig. 14 is a view similar to Fig. 11, showing one of the dies and the shearing knife in engagement with the blank. Fig. 15 is a side view of one of the ends of the blank, showing the burs formed on the blank by the cutting die, and Fig. 16 shows one end of the blank with the cut completed.

The invention is specially important for the cutting of screwthread by means of the well known screwthread cutting rolls, in which a flow or displacement of the bolt material takes place so that the outer edges of the screwthread project beyond the circumference of the bolt, or the outer diameter of the screwthread becomes larger than the diameter of the bolt. If, for instance, the bolt shown in Fig. 1 of the drawing, of a diameter a , were brought on the rolling machine for cutting screwthread, it would get a screwthread with an outer diameter a_m , as shown in Fig. 2. If it were therefore desired, to produce a screwthread, the outer diameter of which is equal to the diameter of the bolt, the portion of the bolt to be provided with the screwthread, would have to be first turned down to the extent x as shown in Fig. 3, whereupon the rolling machine for cutting screwthread would produce the desired screw bolt shown in Fig. 4. According to this invention, however, it is possible to cut on the rolling machine a screw thread, the outer diameter of which is equal to the outer diameter of the bolt, without it being necessary first to turn down the portion of the bolt to be provided with screwthread. This is effected by a shaving being constantly cut away from the outer screwthread edge, the thickness of the said shav-

ing corresponding to the extent to which the screwthread made projects beyond the diameter of the bolt. To that end, between the two jaws of the rolling machine is arranged 5 a cutter adjustable in a direction parallel to the said jaws, resting against the bolt to be rolled between the two jaws, and acting in the manner shown in Figs. 5 to 8. Of the said figures, Figs. 5 and 6 are two sections, at a right angle to each other, through the axis of the bolt, while Figs. 7 and 8 show the corresponding plans. As will be seen, the cutter M has such a shape that at 10 the same time it rounds off the end of the bolt. Two such cutters of course could be provided, or separate cutters could be provided for the treatment of the end of the bolt, which would constantly cut away the material forced forward at the end of the bolt, keeping the desired rounding of the 15 end of the bolt.

The single stages of the process are diagrammatically illustrated in Fig. 9. It is assumed in this case, it is a machine with a 20 movable jaw B and a fixed or stationary jaw B'. At the beginning of the treatment, the cutter M has the position shown at I in Fig. 9. As soon as the bolt S has been brought by the movable jaw B to the cutter M (II) the latter becomes operative and 25 during further movement of the bolt goes back with it. Shortly before the end of the rolling process, an accelerated movement is given to the cutter M, so that it moves away 30 from the bolt S (III). In order to obtain a Whitworth screwthread without an outer flattening, the position must be such that the cutter, during its action, should cut away 35 a thicker shaving than would be necessary 40 for keeping the proper diameter of the bolt, namely thicker to the extent to which, during the last rolling stage, after the removal of the cutter from the bolt, the outer screwthread edge is forced outward. As will be 45 seen at IV the cutter goes back to such an extent that the finished bolt can freely leave the jaw. In that way, a perfect Whitworth screwthread is obtained, the outer diameter 50 of which is exactly equal to the diameter of the bolt.

For more fully explaining the improved process in Fig. 10 various stages of the same are illustrated on an exaggerated scale, the example selected for illustration purposes 55 being the manufacture by rolling of a screw in which the outer diameter of the thread has to be exactly the same as that of the shank.

Fig. 10 shows in end elevation, Fig. 11 in 60 side elevation the position of the cylindrical screw blank and the upper or movable rolling die B' at the beginning of rolling. In this stage of the process the die B' is out of contact with the screw blank and so is also 65 the knife M; therefore the lengthwise con-

tour of the blank shown in Fig. 12 has in this stage of the process not yet undergone any change. After the die B' has moved lengthwise through a certain distance the ribs of the same have penetrated into the 70 metal of the blank as shown in end elevation in Fig. 13 and in side elevation in Fig. 14 with the result that the metal of the blank is forced outward between such ribs and the lengthwise contour of the blank shows the 75 configuration shown in Fig. 15, in which 1, 1 indicate the burs formed on the blank at the sides of the ribs of the die B' entered into the metal of the blank. At the same time the knife M has so far approached the 80 blank that it cuts off the said burs leaving the outer diameter of the thread, the same as that of the shank as shown in Fig. 16. As the movement of the die B' continues its 85 ribs penetrate more deeply into the material of the blank whereby fresh material is forced outward forming burs 2 as indicated in Figs. 17, 18 and 19 showing views similar to Figs. 13, 14 and 15 respectively. The 90 knife M, however, still more approaches the 95 axis of the blank as shown in Fig. 18 so that it not only cuts off the burs 2 whereby the outer diameter of the thread is reduced as compared with that of the shank of the blank as seen from Fig. 19 in which the full 100 line shows the configuration of the lengthwise contour of the blank imparted to it by the die B' and the dotted line indicates the configuration of this contour after the knife M has made its cut. Therefore as the die 105 B' approaches the end of its stroke the part of the blank on which the screw thread is being produced is of a smaller diameter than the shank of the blank as is shown in dotted lines in Fig. 20 which is an end elevation corresponding to Fig. 13. The ribs of the die fully penetrating into the blank force out the metal of the same so that it 110 completely fills the grooves between the said ribs, the distance of the bottoms of such grooves from the axis of the blank being exactly equal to the radius of the shank as indicated in full lines in Fig. 20 and in Fig. 21 (corresponding to Fig. 14). In this 115 last stage of the movement of the die the knife M has receded from the blank as seen from Fig. 1 and thus leaves the thread produced by the dies unaltered as seen from Fig. 22. The screw thread on the bolt is thus finished, its outer diameter being exactly equal to the outer diameter of the shank and the screw is ready for use. 120

I claim:—

A process for producing circumferential recesses in bodies of revolution, such recesses having a predetermined depth relatively to the outer surface of the body of revolution consisting in rolling such blanks between dies and during rolling first cutting away the material forced out under the ac- 130

tion of the dies beyond a predetermined limit and in addition thereto a part of the material within such limits and then interrupting such cutting but continuing rolling whereby the material forced out in the latter stage of rolling is forced into the place of the material cut off within such limit in the previous stages of rolling and cutting

and the depth of the recesses attains the predetermined value. 10

In testimony whereof, I affix my signature, in presence of two witnesses.

JULIUS HELLER.
